UNITED STATES PATENT OFFICE.

JOHN R. JEWETT, OF WOOD RIVER, NEBRASKA.

VAULT-MOLD.

1,114,266.

Specification of Letters Patent.

Patented Oct. 20, 1914.

Application filed August 11, 1913. Serial No. 784,185.

To all whom it may concern:

Be it known that I, JOHN R. JEWETT, a citizen of the United States, residing at Wood River, in the county of Hall and State 5 of Nebraska, have invented certain new and useful Improvements in Vault-Molds, of which the following is a specification.

This invention relates to molds for forming cement or concrete burial vaults, and its 10 object is to provide a mold for the lid of the vault which is simple in construction and which enables the lid to be cheaply and expeditiously made. This object is attained by means of a novel combination and arrangement of parts to be hereinafter described 15 and claimed, reference being had to the accompanying drawings in which—

Figure 1 is an elevation of the mold for the lid of the vault; Fig. 2 is an end view 20 of the lid mold; Fig. 3 is a plan view of the lid mold; Fig. 4 is a cross-section on the line 13—13 of Fig. 3; Fig. 5 is a longitudinal section on the line 14—14 of Fig. 3; Fig. 6 is a cross-section of the knife or 25 scraper used for forming the top of the lid; Fig. 7 is a plan view of the pallet for the lid; Fig. 8 is an elevation of the knife or 30 scraper illustrating the manner in which it is used; Fig. 9 is an inverted plan view of the upper part of the lid mold; Fig. 10 is an elevation and Fig. 11 is a plan view of a reinforcement for the lid; Fig. 12 is a front 35 elevation and Fig. 13 is a side elevation of a fastening to be hereinafter described.

Referring specifically to the drawing, the lid to be molded is indicated by the reference character 23. The mold for forming the lid has sides 24 and ends 25. The ends are between the sides and the latter project 40 beyond the ends and are connected by cross rods 26. The end members are prevented from moving along the side members by angle irons 27, and they seat on a bottom frame or pallet constructed of cross timbers 45 or sills 28 on which are placed and secured longitudinal side bars 29 and end cross bars 30. Between the end bars and the adjacent sills extend braces 31. On the pallet is placed a form 32 which is shaped to conform 50 to the arched shape of the lid 23. This form seats inside the bars 29 and 30 of the pallet and rests on the sills 28, the ends of the form seating on the braces 31, whereby it is se-

curely held in place. The sides and ends of the form coincide with the inner edges of 55 the bars 29 and 30. On the under side of the form are struts 33 to strengthen the same and enable it to withstand the weight of the material forming the lid. The form is composed of flooring which is laid on the struts, 60 the latter being shaped and arranged to arch the flooring. In order to make the form as smooth as possible, the flooring is covered with sheet metal, as indicated at 34. The outer edge of this sheet metal covering laps 65 over to the end and side members 25 and 24.

In order to prepare the mold ready to receive the concrete material to form the lid 23, the form 32 is placed on the pallet as hereinbefore described, and the side and end 70 members 24 and 25 used for forming the sides and ends of the lid are put in place. Concrete material is now placed on the form and between the same and the side and end members 24 and 25. Two arched reinforcing bars 36 extending transversely of the lid are then suspended by means of hook bolts 37 from cross bars 38 carried by posts 39 rising from the side members 24, and a reinforcement is placed on the material. The 75 form is now filled to the upper edge of the members 24 and 25 and rounded off and brought down to a finish by an arched scraper 40 shown in Figs. 6 and 8, by sliding said scraper along the side members 24. The 80 bars 36 are embedded in the lid and have loops 41 intermediate their ends which project from the top of the lid, forming eyes 85 to facilitate the handling thereof.

In order that the finished lid may be removed from the mold, the side members 24 are provided with angle brackets 42 the outstanding portions of which have slots 43 through which pass bolts 44 rising from the side bars 29 and secured by wing nuts 45. 95 Upon loosening the wing nuts the side members can be moved away from the molded lid by reason of the slots 43.

The parts herein described are economically constructed and they are light and thus 100 easily handled. The sheet metal lining not only gives the concrete a smooth surface, but also protects the wooden frames from moisture, and thus prevents warping.

I claim:
A mold for vault lids comprising a bottom

composed of cross sills, and side and end bars mounted on top of said cross sills, an arched form resting on the cross sills and fitting between the side and end bars, the 5 sides and ends of the form coinciding with the inner edges of the side and end bars, and side and end members mounted on the afore- said side and end bars, and surrounding the

sides and ends of the form in spaced relation therewith.

In testimony whereof I affix my signature in presence of two witnesses.

JOHN R. JEWETT.

Witnesses:

W. E. DONNER,
C. H. GOOD.
